PHILLIPP J. MARCHAL, OF HARTFORD, CONNECTICUT.

Design No. 4,006, dated May 3, 1870.

DESIGN FOR A BURIAL CASKET.

The Schedule referred to in these Letters Patent and making part of the same.

I, PHILLIPP J. MARCHAL, of Hartford, in the county of Hartford and the State of Connecticut, have invented a new and original Design for Burial Caskets, of which the following is a specification.

The nature of my design is fully represented in the accompanying drawing, to which reference is made.

The letter *a* indicates the head of the casket.

b, the side, which may be made of wood, metal, or other suitable material.

It will be observed—

First, that the whole top swells from the sides in such fashion that a cross-section of the same is a double ogee.

Second, that the casket tapers symmetrically from the head to the foot.

Third, that the head, and the foot like it, of course, has an ornamental molding, which follows the general outline.

Fourth, that the sides have the same, except that they are broken into diamonds in the center.

Fifth, that the corners are all rounded, and

Sixth, that the top is divided into two panels, bounded by ornamental moldings, all around which runs a flat surface which I call a rail.

The foregoing points are merely matters of description, and are only claimed as a whole herein.

Claim.

I claim as my invention—

The general design for a burial casket, as set forth. Dated January 31, 1870.

PHILLIPP J. MARCHAL.
